JOHN WEST MACMEEKEN, OF GLEN RIDGE, NEW JERSEY, ASSIGNOR TO WORTHINGTON PUMP AND MACHINERY CORPORATION, OF NEW YORK, N. Y., A CORPORATION OF VIRGINIA

CENTRIFUGAL PUMP

Application filed September 29, 1927. Serial No. 222,757.

This invention relates to centrifugal pumps, and more particularly to pumps used for pumping liquids at high temperatures, such as oil in a refinery, where the temperature of the oil varies from a low to a very high temperature.

In centrifugal pump construction, a pump which must deliver a quantity of liquid against a specified head may be much simpler and consequently less expensive to manufacture, if the speed of rotation can be made high enough to enable the generation of head to be accomplished in a single stage pump. When the head delivered against by the pump is relatively high, high rotative speed of the impeller is required and at such speeds it is of great importance that alignment of the shaft and rotative elements be maintained true in the bearings, clearance rings of the impeller and in the stuffing box. It is also of importance for high speeds that the pump shaft remain in alignment with the shaft of the prime mover or driving motor when the latter is directly connected to the pump shaft.

Variations in temperature of the fluid pumped, especially when very high temperatures are reached, will result in expansion or contraction of the pump parts, which would in ordinary approved constructions of centrifugal pumps, seriously affect the alignment of the rotative elements of the pump, and its operation, and it is an object of the present invention to provide a pump structure which will ensure proper alignment of the shaft and rotating elements during temperature variations from the lowest possible degree to the highest operating temperature at which the liquid is to be pumped.

More specifically, the present invention comprises a centrifugal pump, constructed and designed throughout to permit maximum dissipation of heat and minimum transferring of heat, from the liquid being pumped, to the bearings and bearing supports and also embodies provision for cooling the bearings and permitting only movement of the pump casing axially or parallel to the shaft, thereby preventing misalignment of the bearings, pump shaft and shaft

of the prime mover and the resultant disadvantages and dangers of impairment of operation of the pump.

Another object of the invention is to provide a centrifugal pump for pumping hot liquids in which the number of joints in contact with high temperature liquid are reduced to a minimum, thereby reducing dangers contingent with leakage of fluid being pumped and one in which the one joint, necessary for assembly of the pump, so subjected is located, where there is no differences in temperature at its sides.

In the preferred form of the invention, the above objects are attained by rotating the shaft in bearings which are centred in a cool pedestal or frame, unaffected, or affected only to a slight degree, by the heat of the fluid, and the pump casing, due to the fact that the frame or pedestal has an air cooled joint and the minimum necessary contact with the pump casing, therefore only the minimum passage of heat from the casing to the frame will take place. The joint between the pump casing and the frame or pedestal is also so designed that radial movement under heat expansion may be prevented and only axial movement, or movement of the casing parallel to the shaft will take place, which movement does not affect the adjustment of the rotor in the bearings and impeller clearance rings.

Means are provided in the pump structure which while they offer no appreciable resistance to expansion or contraction of the casing, under temperature variances, in an axial direction, they resist any transverse movement from strains in external piping and resist any turning movement which might result from strains from the discharge pipe.

With these objects in view, the invention consists in various features of construction and combination of parts, which will be first described in connection with the accompanying drawings, showing a centrifugal pump of the preferred form embodying the invention, and the features forming the invention will be specifically pointed out in the claims.

In the drawings:

Figure 1 is a side elevation of the improved pump showing it coupled to a motor which serves as prime mover for the pump.

Figure 2 is an end elevation of the pump.

Figure 3 is a longitudinal section through the pump.

Figure 4 is a cross section through the pump, taken on the line 4-4 of Figure 3.

Figure 5 is a top plan of the base plate of the pump.

Figure 6 is an enlarged view, partly in section, showing the connection of the pump casing with the base plate.

Figure 7 is a longitudinal section through a modified form of the pump.

Referring more particularly to the drawings, the improved pump which is shown in the drawings is a single stage or single impeller centrifugal pump, primarily designed for the pumping of hot fluids such as petroleum oil during its circulation through a refinery and includes the pump casing 1 which is formed of the suction or inlet section 2 and

what is herein called the bearing section 3. The sections 2 and 3 of the pump casing are constructed so as to facilitate assembly of the pump and the proper mounting of the impeller 4 in the casing and on the impeller driving shaft 5.

The sections 2 and 3 are connected in approved manner, such as by bolts 6 and their point of contact as indicated at 7, provides the only pressure joint in the entire pump construction.

The suction or inlet to the pump impeller is axial, through the inlet 8, while the discharge from the pump is through the volute or diffuser 9 and discharge outlet 10, such construction being usual in centrifugal pumps. The usual impeller rings

11 are employed in the pump structure and any approved means, as indicated at 12, may be provided for connecting the impeller 4 to the shaft 5. In maintaining proper performance of a centrifugal pump of this type, it is

vitally necessary that the shaft 5 and impeller 4 remain in alignment, that the impeller remain in proper alignment and position relative to the impeller rings 11 and also that the

shaft 5 remain in proper alignment with the shaft 14 of the prime mover 15 when the pump shaft 5 is directly coupled to the shaft 14 as shown in Figure 1 of the drawings. To accomplish the above, the shaft 5 rotates in bearings 17 which are centred in a cool pedestal

18. The pedestal 18 is supported upon suitably finished surfaces 19 on the bed plate 20 and the pump structure and has a rabbeted metal to metal joint 21 with the section 3 of the pump casing. The joint 21 is preferably

drilled at circumferentially spaced points as shown at 22 and it is so designed as to provide minimum contact between the pedestal 18 and the section 3 of the pump casing 1, thereby permitting very little transmission of heat from the casing 1 to the pedestal 18. The pedestal

18 is provided with a flange 24, which is connected by bolts 25 to a flange 26 formed on the section 3 of the pump casing 1. By particular reference to Fig. 3 of the drawings, it will be noted that the flanges 24 and 26 are spaced apart so as to permit air cooling of the bolts 25 and also that the flange 26 is spaced from the main impeller enclosing part of the section 3 and the casing 1, so as to permit circulation of air between the flange 26 and the impeller enclosing part of the section 3 to allow cooling of the flange and dissipation of heat; the entire construction being designed so as to permit the maximum dissipation of heat from the flange 26 and the minimum transfer of heat to the pedestal 18, so as to render the bearings unaffected in alignment by temperature variations in the casing 1. The pedestal 18 is provided with a plurality of air openings 28 which permit free circulation of air to facilitate the removal of any heat which might travel along the casing and casing extension 29 into the interior of the pedestal 18.

Cooling of the bearings 17 is accomplished by the admittance of cool oil under a pressure greater than the suction pressure of the pump to the interior of the casing extension 29 through the pipe 30. The cool oil travels along the groove 31 in the forward bearing 17 toward the impeller 4, lubricating the bearing and passing into the balancing chamber 32 of the pump, from which it passes out through the vent pipe 33. This leakage of cool oil through the groove 31 cools the shaft 5 and reduces the temperature in the balancing chamber 32, providing a chamber of intermediate temperature between the hot and cold elements of the pump. If any of the cool oil vaporizes with the increase of temperature in the balancing chamber 32, the vapor thus formed will escape through the pipe 33 so that the impeller 4 cannot become vapor bound from this source. Any leakage through the impeller rings 11, into the balancing chamber 32, will mix with the cool oil and be carried out through the pipe 33, so that if the vent pipe 33 is connected to a chamber having the same pressure as the suction of the pump, the impeller will be hydraulically balanced. This construction and directional flow of the cool oil permits the placing of a bearing close to the impeller, thus reducing the reaction of the load on the bearing in accordance with the best practice. This is possible with the direction of flow of cool oil without resulting in too high a temperature in the bearing; however, without sufficient flow of cool oil towards the impeller, the oil in the bearing would be in danger of losing its physical and chemical qualities due to decomposition under temperature for a duration of time.

Cool oil also travels through the groove 34 formed in the outer bearing 17 and through the stuffing box 35 where it lubricates the packing 36 in the stuffing box, thereby seal-

ing the casing with cool oil and cooling the shaft 5 and packing 36.

From the foregoing description, taken in connection with the drawings, it will be apparent that: by the extending of the pump casing 1 in the dish shaped flange 26 continuous with the curvature of the casing 1: the rabbeted metal to metal joint 21 between the pedestal 18 and casing 1, together with the drilled openings 22 therein, which provide the minimum necessary contact between the casing and pedestal, as well as the spacing of the flanges 24 and 26 to permit circulation of air about the coupling bolts 25: the maximum dissipation of heat with the minimum passage of heat from the pump casing 1 to the pedestal 18, which holds the alignment of the bearings, will be provided.

In addition to the above features and the cooling of the bearings 17 by cool oil, the free circulation of air within the pedestal 18, which is provided by means of openings 28, will convey away such heat as may pass to the inside of the pedestal, so that the alignment of the bearings and the pedestal will remain unaffected by temperature changes of the casing 1 and of the fluid being pumped, thereby preventing misalignment of the shaft 5 and impeller 4. It will be noted by reference to the drawings that the oil introduced for cooling the bearing surfaces does not mix with the oil or fluid passing through the pump and therefore has no adverse effect on the process of refining the oil being pumped and does not affect the temperature of oil delivered by the pump.

The casing 1 of the pump will however be subjected to expansion and contraction under temperature variations and the entire design of the pump, including the provision of the dish shaped flange 26, is such as to permit movement of the casing under such expansion and contraction axially or in a direction parallel to the shaft 5 and a construction is embodied in the pump structure which will offer no appreciable resistance to expansion or contraction of the casing in an axial direction, but will resist any transverse movement of the casing from strains in the external pipe 50 which is connected to the pump, or from any other source, and resist any turning movement which might result from strains from the discharge pipe. This construction includes a depending lug 40 formed on the under side of the casing 1. The lug 40 has a groove 41 cut therein, which extends parallel to the shaft 5 and slidably receives a key 42. The key 42 fits in a groove 43 formed in the upstanding boss 44 and it is attached to the boss carrying member 45 in any suitable manner, such as by a cap screw 46. The member 45 in turn rests upon a finished surface on the bed plate 20. The bed plate 20 has upstanding pedestals 47 thereon upon which suitable supporting lugs 48 formed on the pump

casing 1 rest. The slidable supporting connection formed between the pump casing section 3 and the bed plate 20 by means of the boss 40, key 42 and member 45, will permit movement of the pump casing parallel with the shaft but will resist or prevent movement of the casing transversely of the shaft, thereby, with the other features previously described, providing maintenance of proper alignment of the rotative parts of the pump with their respective companion stationary parts, and efficient, proper operation of the pump will be permitted under any and all temperatures to which the pump is subjected and under the variations of such temperatures.

In Fig. 7 of the drawings, a modified form of the improved pump is shown, which pump is similar in many respects to the preferred form illustrated in Figs. 1 to 6 inclusive. However, the construction shown in Fig. 7 is applicable for pumps of smaller size and capacity than the type shown in Figs. 1 to 6.

In the modified form of the invention, the shaft 50 which carries the impeller 51 is mounted in a single bearing 52 which is carried by the sleeve 53 formed on the section 54 of the pump casing 55 and the bearing 52 and sleeve 53 are centred in the cold or cool pedestal 56, which corresponds to the pedestal 18 in the preferred form of the invention. As in the preferred form of the invention, a cooling oil supply pipe 57 passes through the sleeve 53 and delivers cooling lubricating oil to a groove 58 in the bearing 52 and said oil passes along the shaft 50 towards the impeller 51, into the balancing chamber 59 from which it is carried off by the vent pipe 60. The pedestal 56 is mounted upon a suitable supporting base in the same manner in which the pedestal 18 is mounted and it has air circulating openings 61, to permit circulation of air in the pedestal, and about parts of the section 54 of the casing 55 for dissipating the heat.

The pump casing 55 is formed of the sections 54 and 62 which are connected by a pressure joint 63, the said joint being the only pressure joint in the pump structure. The section 54 has formed thereon the connecting flange 64 which is dish shaped and continues in the curvature of the casing 55 for providing maximum circulation of air about the flange 64 and expansion and contraction of the casing, due to temperature variances, in a bellows-like manner. The flange 64 is connected by rabbeted joint 65 and bolts 66 with the flange 67 on the pedestal 56. The flanges 64 and 67 are spaced so as to permit circulation of air about the bolts 66. In fact, the modified form of the pump is similar in construction and operation to the preferred form in all respects with the exception that the shaft 50 has a single bearing 52 in lieu of the multiple bearing 17.

In both the preferred and the modified

forms of pumps, a ball bearing structure 70 of approved form is illustrated, which is a bearing capable of both radial and axial load. These, or equivalent bearings make the pump 5 a self-contained machine, which may be coupled by means of the coupling 71 direct to a standard commercial motor as shown at 15, or other suitable prime mover.

It will also be apparent that by the maintaining of proper alignment of the rotary parts of the pump with the stationary parts of the pump, proper alignment between the shafts 5 and 14 will also be maintained, and while the prime mover 15 is shown as an electric motor, it is to be understood that any suitable type of prime mover may be employed without departing from the spirit of this invention.

It will be understood that the invention is 20 not to be limited to the specific construction or arrangement of parts shown but that these may be modified widely within the invention defined by the claims.

What is claimed is:

- 25 1. In a centrifugal pump for pumping hot liquids, a pump casing, an impeller therein, a shaft for rotating the impeller, a supporting pedestal, said casing having a dish shaped connecting flange continuous with the curvature of the casing, and having spaced, bolted connection to the pedestal to permit air cooling of the flange and bolt connection for the dissipation of heat.
- 30 2. In a centrifugal pump for pumping hot liquids, a pump casing, an impeller therein, a shaft for rotating the impeller, a supporting pedestal, said casing having a dish shaped connecting flange continuous with the curvature of the casing, and having spaced, bolted connection to the pedestal to permit air cooling of the flange and bolt connection for the dissipation of heat, said flange having a relatively small metal to metal contact with the pedestal to reduce to a minimum transmission of heat from the casing to the pedestal.
- 35 3. In a centrifugal pump for pumping hot liquids, a pump casing, an impeller therein, a shaft for rotating the impeller, a supporting pedestal, said casing having a dish shaped connecting flange continuous with the curvature of the casing and having spaced, bolted connection to the pedestal to permit air cooling of the flange and bolt connection for the dissipation of heat, and having a relatively small rabbeted metal to metal contact with the pedestal, said rabbeted contacting parts being drilled at circumferentially spaced points to reduce to a minimum the contact between the casing and pedestal.
- 40 4. In a centrifugal pump for pumping hot liquids, a pump casing, an impeller therein, a shaft for rotating the impeller, a supporting pedestal, said casing having a dish

shaped connecting flange continuous with the curvature of the casing and having spaced, bolted connection to the pedestal to permit air cooling of the flange and bolt connection for the dissipation of heat, bearings 70 for the shaft centred in said pedestal, said bearing adapted to receive cooling fluid under pressure for cooling said bearings, whereby the shaft and impeller will remain in alignment during temperature variations of 75 the casing.

5. In a centrifugal pump for pumping hot liquids, a casing, an impeller therein, a shaft for rotating the impeller, a prime mover including a shaft direct coupled to the pump 80 shaft, a supporting pedestal, said casing having a dished connecting flange continuous with the curvature of the casing, a flange on the pedestal and disposed in spaced relation to said dished connecting flange and bolted thereto for connecting the casing and pedestal to permit air cooling of the flanges for dissipation of heat, said casing and pedestal having relatively small metal to metal contact, whereby transmission of heat from the 85 casing to the pedestal will be reduced to a minimum to permit maintaining of alignment of the impeller, pump shaft and prime mover shaft.

6. In a pump for pumping hot liquids, a 90 pump casing, an impeller, a shaft for rotating the impeller, a supporting pedestal, said casing having a dish shaped connecting flange continuous with the curvature of the casing and having spaced, bolted connection to the pedestal to permit air cooling of the flange and bolt connection, a balancing chamber in said casing, a bearing for the shaft centred in said pedestal, said bearing arranged to permit circulation of cooling liquid 100 about and through the bearing along the shaft into said balancing chamber.

7. In a centrifugal pump for pumping hot liquids, an impeller, a driving shaft, a casing having only one joint subjected to pressure 110 of fluid pumped, said casing having a vented balancing chamber therin, said casing extending beyond the balancing chamber, both radially in a dish shaped, air cooled flange and axially in the form of a shaft surrounding sleeve, said sleeve being spaced from the shaft, a bushing in the space between said sleeve and shaft, a stuffing box at the outer end of the sleeve, a supporting pedestal provided with air circulating openings, said 120 sleeve being centred in said pedestal and cooled externally by air circulation and internally by the flow of cooling fluid, whereby its axis will be coincident both with the axis of the pump shaft and with the axis of the 125 prime mover shaft irrespective of the temperature of the fluid pumped.

8. In a centrifugal pump for pumping hot liquids, a prime mover shaft, an impeller, a pump shaft, a casing having a shaft-sur- 130

- rounding bearing-retaining sleeve formed thereon, a supporting pedestal provided with air circulating openings, said sleeve being central in said pedestal and cooled externally by air circulation and internally by the flow of cooling fluid, whereby its axis will be coincident both with the axis of the pump shaft and with the axis of the prime mover shaft irrespective of the temperature of the fluid pumped.
9. In a centrifugal pump for pumping hot liquids, an impeller, a pump shaft, a driving shaft, a casing having a vented balancing chamber therein, said casing extending beyond the balancing chamber axially in the form of a shaft-surrounding bearing-retaining sleeve, a supporting pedestal, said sleeve being central in said pedestal and cooled externally by air circulation and internally by the flow of cooling fluid, whereby its axis will be coincident both with the axis of the pump shaft and with the axis of the driving shaft irrespective of the temperature of the fluid pumped.
10. In a centrifugal pump for pumping hot liquids, a pump shaft, a driving shaft, a casing having a vented balancing chamber therein, said casing extending beyond the balancing chamber axially in the form of a shaft-surrounding bearing-retaining sleeve, a supporting pedestal, said sleeve being central in said pedestal and cooled externally by air circulation and internally by the flow of cooling fluid, whereby its axis will be coincident both with the axis of the pump shaft and with the axis of the driving shaft irrespective of the temperature of the fluid pumped.
11. In a centrifugal pump for pumping hot liquids, a pump casing, an impeller within the casing, a shaft for said impeller, a bearing for the shaft, said pump casing having a balancing chamber therein sealed from the fluid channel of the pump casing, said bearing arranged to permit circulation of cooled oil about and through the bearing along the shaft towards said impeller and into said balancing chamber.
12. In a centrifugal pump for pumping hot liquids, a pump casing, an impeller rotatable therein, a shaft for the impeller, a bearing for the shaft, said casing having a balancing chamber therein sealed from the fluid channel of the pump casing, said bearing arranged to permit circulation of cool oil, about and through the bearing along the shaft and into said balancing chamber, and an outlet from said balancing chamber for the oil passing thereto, whereby cooling and lubricating oil will be circulated in the bearing and balancing chamber without entering the fluid passage of the casing.

In testimony whereof I affix my signature.
JOHN W. MACMEEKEN.
